CLAIM

The ornamental design for a combined water bottle and drinking tube for animals, substantially as shown and described.

DESCRIPTION

FIG. 1 is a front elevational view of a combined water bottle and drinking tube for animals showing my new design;

FIG. 2 is a left side elevational view thereof, the right side being a mirror image of the left side shown;

FIG. 3 is a rear elevational view thereof;

FIG. 4 is a top plan view thereof; and

FIG. 5 is a bottom plan view thereof.
